Washing Machine,

Patented May 25, 1832.

Eya Disk.

Letters Patent Dated May 25 1832.

The schedule referred to in these Letters Patent, and making part of the same, containing a description in the words of the said Eya Disk himself, of his improvement in the Washing machine.

It will be when these presents shall come:

Be it known that Eya Disk of Fayette in the County of Penobscot, and State of Maine, have invented a new and useful improvement in the washing machine, and that the following is a full and exact description of the construction and operation of the said machine, as invented or improved by him.

This machine is constructed to work in an oblong square box or tub, which admits of various sizes. But for ordinary use in private families, the tub may be about thirty inches in length eighteen inches in width and twelve inches in depth; and in this tub is placed a curved apron which consists of two side pieces of some suitable kind of hard wood board, nineteen inches in length, two inches in width, and one inch in thickness.

These pieces are placed in the sides of the tub with the concave edges upwards one end of each resting on the bottom of the tub - the other end elevated about nine inches, and resting against the front end of the tub, in which position they are covered with a board of some suitable kind of hard wood which extends along the whole width of the tub, and across the whole length of the side pieces excepting about three inches at

the elevated ends. The upper surface of the board is fluted or reeded like a common wash board.

To prevent the apron from sliding on the bottom of the tub, small blocks are attached to the sides of the tub at the bottom. The reeded board of the apron is confined to the side pieces by suitable mortise screws. A rubber is constructed to operate on the apron, consisting of two side pieces about nine inches in length three inches in width & three-fourths of an inch in thickness. These pieces are placed on the apron about fourteen inches in width, the lower edges being convex so as to correspond to the curve of the apron, and the upper edges curved, or hauled, so as to reduce the width to two inches at the ends. The side pieces of the rubber thus described, are connected by several pieces of board, say three or four in number one inch in width and three-fourths of an inch in thickness, with suitable tenons on the ends that are inserted in corresponding mortises made in the side pieces so as to leave a space of one inch between them, the under side of the pieces being reeded.

The reeded surfaces of these pieces form a level with the convex edges of the side pieces, and the vacant spaces between them are occupied by rollers that are seven eighths of an inch diameter, with small wedges of iron or other hard metallic substance inserted in the ends; and the whole is marsh in small proportion, one-fourth of one inch diameter, made in the side pieces so that the rollers project one-fourth of an inch below the reeded surface. Of the intervening pieces, one roller is also placed at each end of the side pieces. Circular preparations three-fourths of an inch diameter, are made thro the

side pieces of the rubber, at the centre (as respects the length) about one inch below the upper edge.

The rubber thus constructed, is suspended by a kind of frame work that is supported by two posts which may be two inches in width and one inch in thickness. These posts are attached to the outer sides of the tub, about seven inches from the rear end, extending in a vertical position, twenty two inches above the tub, and the posts are confined in their position by sinking the lower ends in dovetail form into the sides of the tub, or they may be confined by any other suitable kind of fastening.

The upper ends of the posts are connected by a cross piece of wood which may be either square or round, about one inch and a half through, with grooves made on the ends, fitted to work in round perforations, three fourths of an inch diameter, made thro' the posts, one inch below the upper ends. Two perforations which may be either round or square, are made thro' the above described cross piece, about two inches from the posts and in these perforations are inserted the ends of two pieces of wood that extend in the rear about seven inches, the outer and ends being about one and a half deep, and three fourths of an inch thick, and thro' these, about an inch from the rear end, are made horizontally, round perforations, three fourths of an inch diameter and these ends are connected by a cross piece that may be either square or round, about an inch and one fourth through, with grooves on the end fitted to work in the last

mentioned perforations. Two round perforations, three-fourths of an inch diameter, or square mortices equivalent, are made thru the last described cross piece, one inch and a half from the shoulders of the judgment, and in these perforations, or mortices are inserted suitable tenons made on the ends of two pieces which extend from the last described cross piece down to the rubber as it is at rest on the apron. These pieces measure brevity six inches in length, three-fourths of an inch in thickness, and two inches in width at the lower ends; but the width diminishes to an inch and one-fourth at the upper ends, the width of the pieces corresponding to the length of the tub.

Round perforations, one inch diameter, are made thru the pieces last described, about an inch from the lower ends, and the ends being placed within the side pieces of the rubber are connected therewith by a roller that is an inch and one-fourth through with judgments on the ends fitted to work in the perforations last mentioned. The judgments pass also thru the side pieces in the perforations made at the centre as before described.

The judgments must work easily in the pieces by which the rubber is suspended, but they are confined in the pieces of the rubber by being pinned thru.

The machine, thus constructed, may be worked in any suitable frame fitted to sustain it, or it may be worked on a common wash-bench or any other convenient convenience.

To operate the machine, the clothes must be prepared for washing as in the usual way, and the tub suspended.

with a sufficient quantity of warm water and soap. One large piece or several smaller pieces, may be placed on the apron, duly spread on the needed surface, and the rubber applied with a rugged or gentle motion as occasion may require.

The dumb ends are drawn off by means of a crook, or plier, inserted in the rear end of the tub near the bottom.

Although specific dimensions are stated in the preceding specification of the machine, yet the size and proportion of the several parts may be varied to larger or smaller at pleasure, but so as not to vary the general principles of the machine.

The specific, new, and useful improvements comprised in the machine herein before described, and claimed by me, as being the first inventor thereof, are the following:

1st The Rubber, as combining and presenting a surface of rollers intermixed with plaited or reeded pieces, and in its application and use, producing a gentle operation on the clothes, which is in a medium between a squeeze and rub, thereby producing the effect of cleaning, expeditiously and perfectly without mauling the clothes by too heavy friction.

2nd The particular mode of suspending the rubber, being without the aid or resistance of weights or springs.

3rd The general manner of combining the parts as being now, preparing in a high degree the advantages of regularity, and ease, not liable to get out of order, and in the operation resembling very

nearly the common mode of washing, consequently requiring but little practice to become acquainted with the mode of using the machine - a man -
geously.

In testimony that the above is a true specification of my said improvement as above stated, I have hereunto set my hand & seal the twenty-first day of February in the year of our Lord, eighteen hundred and thirty-two
